UNITED STATES PATENT OFFICE.

WILLIAM H. PERRY, OF CONCORD, NEW HAMPSHIRE.

DESIGN FOR A MONUMENT.

SPECIFICATION forming part of Design No. 23,406, dated June 26, 1894.

Application filed May 24, 1894. Serial No. 512,376. Term of patent 7 years.

To all whom it may concern:

Be it known that I, WILLIAM H. PERRY, a citizen of the United States, residing at Concord, in the county of Merrimac and State of New Hampshire, have invented and produced a new and original Design for a Monument, of which the following is a specification, reference being had to the accompanying drawing.

The essential features of my design consist in the particular configuration of the shaft, its ornamentation, and the different styles of finish adopted for the various parts.

The different features of my design and the various styles of finish are designated by figures and letters of reference on the accompanying drawing.

The base 1, is square having four vertical sides terminating in an obtuse frustum of a pyramid 2. The pedestal 3, is also square, its vertical sides terminating in an acute frustum of a pyramid 4, upon one or more sides of which may be formed the tablet 5. The shaft has four vertical sides 6, ornamented with a tablet 7 of the configuration designated by the marginal or border line 8. The shaft is further ornamented, at its bottom with the raised tablet 9, having the center portion of its upper edges chamfered as at 10, and at its

top with the raised tablet 11, the central portion of the lower edges of which is cut away 30 as at 12. This tablet 11, terminates in a pyramid 13, forming a cap or top finish for the shaft, and is ornamented with raised tablets 14, their lower edges being of the configuration shown at 15. The corners of the tablet 11, are 35 chamfered as at 16.

The vertical sides of the shaft 6, have at each corner a buttress 17, each of which is ornamented with a groove extending nearly its entire length as shown at 18. The monument 40 is further ornamented by a finish of a different character for the various parts, designated by letters of reference,—A representing polished work, B, hammered work, and C, rock-work.

Having described my design, what I claim is—

The design for a monument substantially as shown and described.

In testimony whereof I affix my signature in 50 presence of two witnesses.

WILLIAM H. PERRY.
